CLAIM

The ornamental design for a horizontal placement storage rack for game console set, as shown and described.

DESCRIPTION

FIG. 1 is a perspective view of a horizontal placement storage rack for a game console set showing my design; FIG. 2 is another perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; FIG. 8 is a bottom plan view thereof; and, FIG. 9 is a perspective view thereof in a usage state.

(Continued)

The broken lines in the drawings depict portions of the horizontal placement storage rack for game console set that form no part of the claimed design.

1 Claim, 9 Drawing Sheets
